(57) **CLAIM**

I claim the design for a solar lamp, as shown and described.

DESCRIPTION

FIG. 1 is a perspective view of a solar lamp showing my design;

FIG. 2 is a top plan view of the solar lamp;

FIG. 3 is a left side elevational view of the solar lamp with the right side elevation being identical thereto;

FIG. 4 is a rear elevational view of the solar lamp with the front elevation being identical thereto; and,

FIG. 5 is a bottom plan view of the solar lamp.

The broken lines showing a stand associated with the solar lamp are for illustrative purposes only and form no part of the claimed design.
